SELECTIVELY OPERABLE VENDING
MACHINE

William D. Young and William Andrew Harris,
Greenville, S. C., assignors, by direct and mesne
assignments, of twenty per cent to said Young,
twenty per cent to Dorothy R. Young, twenty
per cent to Betty Jane Young, twenty per cent
to Jean Ann Young, and twenty per cent to
Nancy Lou Young, all of Greenville, S. C.

Application December 13, 1943, Serial No. 514,074

4 Claims. (Cl. 194—48)

This invention relates to a vending machine having a plurality of compartments for holding articles of merchandise with a delivery mechanism associated with each compartment to deliver one article at a time to the exterior of the machine, with coin controlled means for unlocking all delivery mechanisms for delivery of the merchandise to the exterior of the machine, the parts being so arranged that only one of the delivery mechanisms can be operated at a time after the insertion of a coin for unlocking the locking means for the delivery mechanisms for the various compartments.

It is an object of this invention to provide a vending machine having means for holding a plurality of columns of merchandise with delivery mechanism normally supporting each column of merchandise, with delivery mechanism operating means disposed on the exterior of the machine, there being one operating means for each column of merchandise, with coin controlled means for unlocking all of the delivery mechanisms, and means whereupon when one of the delivery mechanisms is operated, the merchandise from the compartment associated with the operated delivery mechanism will be delivered one at a time to the exterior of the machine, the delivery mechanisms having control means which makes it impossible for two of the delivery mechanisms to be operated at the same time, as a result of inserting a coin into the coin controlled means controlling the delivery mechanism.

Some of the objects of the invention having been stated, other objects will appear as the description proceeds, when taken in connection with the accompanying drawings, in which—

Figure 1 is an isometric view of the vending machine;

Figure 2 is a vertical sectional view taken along the line 2—2 in Figure 4 after the upper and lower front covers have been removed, and also showing the coin chute removed;

Figure 3 is a vertical sectional view taken along the line 3—3 in Figure 4;

Figure 4 is a vertical sectional view taken along the line 4—4 in Figure 2;

Figure 5 is a sectional plan view taken horizontally through the machine immediately above the delivery mechanism and substantially along the line 5—5 in Figure 3, omitting members 82 and 83;

Figure 6 is a vertical sectional view taken on an enlarged scale along the line 6—6 in Figure 5, and looking in the direction of the arrows, and omitting the tongues 81;

Figure 7 is a view similar to Figure 6, but showing the delivery mechanism in operated or delivery position;

Figure 8 is an enlarged front elevation of one of the delivery operating mechanisms as they appear in Figure 2;

Figure 9 is a view similar to Figure 8, but showing the parts in delivery position;

Figure 10 is an end elevation on an enlarged scale of the right-hand portion of Figure 4;

Figure 11 is a view similar to Figure 10, but showing the mechanism in a position it will occupy after a coin has been dropped into the apparatus, and immediately prior to operation of the delivery mechanism, for one of the compartments;

Figure 12 is a sectional plan view showing the lower left-hand corner of Figure 5, and being substantially along the line 12—12 in Figure 4.

Referring more specifically to the drawings, the numeral 10 indicates the base of the housing in which the vending mechanism is disposed, while reference character 11 indicates the back, 12 and 13 the two end portions of the casing, while 14 indicates the top of the casing hinged to the rear wall as at 9 and having a hasp 8 fitting over a staple 7 in which a lock is adapted to be disposed. The upper front cover comprises a frame 15 in which a pane of glass 16 is mounted, and the lower front cover comprises a member 17 having a horizontal portion 18 with a plurality of slots 19 therein for fitting around the vertically disposed delivery mechanism operating levers A' to F' to be presently described. The front cover 15 is secured in position by suitable screws 21. The lower front cover 17 is secured in position by any suitable means such as screws 22.

The framework of the vending apparatus which is adapted to be installed within the above-described outer casing comprises end walls 25 and 26 which are flanged at their lower ends, and are adapted to be secured to base 10 of the outer casing by any suitable means such as screws 27. The end walls 25 and 26 have outturned vertically disposed flanges 28 and 29 at the rear edges thereof as viewed in Figure 2.

Secured between the end walls 25 and 26 are side plates 30 and 31 and mounted inwardly from side plate 31 and in spaced relation thereto is an identical plate 32, the purpose of which will be presently described.

Oscillatably mounted between the plates 30 and 32 is a plurality of delivery cylinders designated broadly by the reference characters A, B, C, D, E, and F. Each of these cylinders comprises cir-

cular head members 35 and 36 with an arcuate member 37 having its ends secured to the proximate surfaces of the head member 35 and 36 and extending in an arcuate path for about one quarter of a circle.

The head members 35 have a centrally located pin 38 oscillatably mounted in the front wall 30. Each of the head members 36 has a pin 40 mounted therein and extending into and being oscillatably mounted in the member 32. Each of the head members 35 has a pin 45 extending outwardly therefrom through a slot 46 in the front plate 30, and fitting loosely into an elongated slot 47 in a lateral projection 48 in a vertically movable member, these vertically movable members being identical and being designated by reference characters A', B', C', D', E', and F'.

The upper edge of front wall 30 projects forwardly in the form of a flange 50, and has a plurality of notches 51 therein in which the members A' to F' inclusive are mounted for vertical sliding movement. A bar 52 is spaced forwardly from the wall 30, and is secured to the wall 30 at its ends as at 53 and 54 to loosely and slidably confine the upper portions of the members A' to F' inclusive.

Secured to the lower edge of front wall 30 of the framework of the vending mechanism is an angle bar 58 which has slots in its horizontal portion for loosely and slidably receiving the lower ends of the operating member A' to F' inclusive. The bar 58 has mounted thereon for each member A' to F' inclusive a spring perch 55 on which the upper end of a tension spring 56 is mounted, the lower end of the tension spring being secured to spring perch 57 secured in the lower portion of each of the members A' to F' inclusive to normally hold the members A' to F' inclusive in elevated position, and to also hold the delivery cylinders A to E inclusive in non-delivering position, or in the position shown in Figures 2, 5, 6, and 8.

Each of the head members 36 has one or more notches 60 and 61 therein into which the free end of a dog 62 is adapted to fit to hold the cylinders locked in non-delivery position, as shown in Figures 3, 6, and 8 in which position the arcuate portion 37 supports a column of articles 81. These dogs 62 are pivoted as at 63 between upstanding lugs 64 and 65 rising from plates 32 and 31 respectively, the dogs being loosely and pivotally mounted between these lugs 64 and 65. Each dog has on its other end an outturned tail portion 66, the other end of the dog being turned inwardly through the space occurring between the lugs 64 and 65 to engage the notches 60 or 61 in the head portion 36 of the cylinders A to F inclusive. The end walls 25 and 26 have rearwardly projecting portions 70 and 71 in which are pivotally mounted the free legs of the U-shaped ends of a rod 72. This rod 72 is adapted by gravity to fall downwardly onto the outwardly turned tail portions 66 of the dogs 62 to raise them out of the path of the notches 60 or 61 of the head members 36 of the delivery cylinders.

Mounted between the lower portion of the end walls 25 and 26 is an upwardly and rearwardly slanting sheet member 80 which has tongues 81 projecting upwardly between the delivery cylinders to guide the delivered packages downwardly into the delivery opening 79. Disposed laterally and above the delivery cylinders is a pair of grate members 82 and 83 which have vertically disposed partitions 84 secured therebetween to form flanges

85 and 86 to prevent endwise movement of the packages of merchandise 87 disposed in each compartment 88 above the delivery cylinders.

Each of the cylinder heads 36 has a portion 5 thereof disposed below and inwardly of the lower edge of the plates 31 and 32, and projecting outwardly from each cylinder head 36 is a pin 90 on which is pivotally mounted one end of a sliding control bar 91, 92, 93, 94, 95, and 96. The right-hand end of dogs 62 as viewed in Figures 6 and 7 is heavier than the left-hand end, thus causing gravity to move the dogs downwardly to the position shown in Figure 6 at all times, except when the rod 72 is resting thereon.

15 The plate 71 rises upwardly from the end wall 25 and has pivotally mounted thereon as at 100 a weighted arm 102 having a weight 103 on one end, which has an additional adjustable weight 101 secured thereon by a screw 99, and as at 104 20 the arm 102 has one end of a link 105 pivoted thereto, the other end of this link being pivoted as at 106 to a lever 107 pivoted as at 108 to the portion 71. This lever 107 extends to the left in Figure 4, and enters a slot in the side of a vertically disposed coin chute 110 which registers with an opening 111 in the lid of the housing through which a coin may be inserted. This coin moves the lever downwardly by its weight to the position shown in Figure 11 before the free end 30 of the lever 107 clears the coin chute, and this allows the coin to drop downwardly into the coin box 115. Pivoted as at 106 is a link 116 which extends downwardly and is slidably mounted in a bracket 117. This link 116 has a shoulder 120 35 on one edge thereof adapted to be engaged by the laterally projecting portion 121 of the standing leg 122 of a bell crank lever 124 pivoted at 123 and having a horizontal portion 125. This horizontal portion 125 rests on top of the beveled ends of the control bars 91 to 96 inclusive, and when one of these bars is operated for operation of one of the delivery cylinders, the horizontal leg 125 of the bell crank lever 124 will be raised 40 upwardly to cause the projection 121 of the vertical portion of the bell crank lever to move out from the path of the shoulder 120, and will allow the parts 107, 105, and 102, previously described to return to the position shown in Figure 10. The horizontal portion 125 of the bell crank lever 124 is spaced from the plate 71, and a bracket 130 45 is secured to the plate 71 and extends outwardly and then has a portion projecting on the outside of the horizontal leg 125 of the bell crank lever 124 to prevent this horizontal portion 125 of the bell crank lever 124 from being pushed outwardly by operation of one of the sliding bars 91 to 96 inclusive. The vertically disposed link 116 having the shoulder 120 thereon also has a laterally projecting portion 131 disposed on the side of the link remote from the shoulder, which projects beneath the rod 72, and when the parts are in the position shown in Figure 10, it raises this rod from off of the laterally projecting portions 66 of the dogs 62 and thus allows the heavy 50 ends of the dogs 62 to engage one of the notches 60 or 61, preferably the notch 61, as they only engage the notch 60 as a safety measure in case they should fail to catch in the notch 61.

Pivoted mounted as at 140 is a downwardly depending member 141 which has its lower end projecting inwardly as at 142 in front of the control bars 91 to 96 inclusive, and portion 142 has a slot 143 therein, and also this slot extends upwardly into the vertical portion of the member 141. The end of this slot next to the bars 91 to 96

is flared outwardly into beveled shoulders 145 and 146 so as to cause the depending member 141 to center itself and swing to the proper position when one of the bars 91 to 96 inclusive is moved to the left in Figure 5 in a delivery operation. These shoulders and the slots in the lower end of the depending member 141 insure that only one bar 91 to 96 inclusive can be moved forwardly at a time, as the slot is not big enough for two bars to pass through it at the same time. This insures that only one of the delivery mechanisms can be operated for the insertion of a coin. The member 141 is prevented from moving outwardly by a bracket 147 secured to plate 71.

Method of operation

When a machine of this type is installed, the compartments 88 are filled with suitable articles of merchandise 87 which may be circular as shown, or rectangular in cross-section, or of any desired shape. These columns of merchandise are supported by the quadrants 37 and are visible to the purchaser. The purchaser drops a coin or check into the coin slot 111, and it falls downwardly in coin chute 116 until it hits the free end of the lever 107, which overcomes the counter weight 103 and the lever is swung downwardly. This moves the link 116 downwardly, and causes the projection 121 of bell crank lever 124, due to the fact that the end 125 of the bell crank 124 is heavier, to fall above shoulder 120, and lock the mechanism in the position shown in Figure 11. The bail 72 resting on arm 131 of link 116 drops with link 116 and bears upon the tails 66 of pawls 62, thereby lifting the other end of these pawls from notches 60 of disks 36. The customer then depresses his choice of one of the operating members A' to F' inclusive. This oscillates the associated supporting member connected with the operating member, which may be any one of the members A to F inclusive, and this moves the parts from the position shown in Figures 2, 6, and 8 to the position shown in Figures 7 and 9, which allows the columns of merchandise supported by quadrant 37 to move downwardly against the concave surface of quadrant 37. At the same time, due to the fact that by downward movement of link 116, projection 131 is moved downwardly which allows the bail or wire 12 to depress all of the laterally projecting tail portions 66 of the dogs 62, and causes all of the dogs to occupy the position shown in Figure 7. This permits any one of the members A to F inclusive to be moved a quarter revolution as previously described. As any one of members A to F inclusive moves a quarter of a revolution, the pin 90 pivotally supporting one end of one of the bars 91 to 96 inclusive causes this bar to move to the left in Figure 5, and its upper corner being beveled will ride beneath and raise portion 125 of bell crank lever 124, and release projection 121 from shoulder 120 and allow the parts to assume normal position as shown in Figures 4 and 10, but the selected member A to F inclusive has already been rotated to where the lowering dogs 62 will not engage in its notches 60 or 61. As any one of bars 91 to 96 inclusive move further forwardly by downward depression of any one members A' to F' inclusive, the left-hand end of the bar so moved as shown in Figures 5 and 12 will strike against one of the sloping surfaces 145 or 146 of swinging member 141, and this member will be swung to cause the operating bar to pass through slot 143. As this slot is only wide enough to permit passage of one of the bars at

a time, it is therefore impossible for two or the operating means A' to F' inclusive to be operated at one time as a result of the dropping in of one coin.

5 When the operator has fully depressed one of the members A' to F' inclusive, he releases the same, and its associated tension spring 56 returns it to normal position as shown in Figure 8. This causes the quadrant 37 to move between the lowermost package and the next lowermost package, and allows the lowermost package to fall downwardly into delivery compartment 79 which is open at its front end.

In the drawings and specification, there has been set forth a preferred embodiment of the invention, and although specific terms are employed, they are used in a generic and descriptive sense only and not for purposes of limitation, the scope of the invention being defined in the 20 claims.

We claim:

1. In a vending machine having a plurality of compartments for holding packages of merchandise, a delivery mechanism for each compartment, tension means normally holding each delivery mechanism in a position to prevent egress of a package of merchandise therefrom, means associated with each delivery mechanism for moving a delivery mechanism to deliver an article of 25 merchandise, locking means for each delivery mechanism adapted to normally lock a delivery mechanism against movement, coin controlled means for moving all of the locking means for the delivery mechanisms to unlocking position 30 upon insertion of a coin, a pivoted slotted member, a bar associated with each delivery mechanism and adapted to be advanced through the slot in the pivoted slotted member upon actuation of a delivery mechanism, the slot in the slotted 35 member being of a width sufficient to allow passage of only one bar at a time to thus prevent the actuation of more than one delivery mechanism upon the insertion of one coin, and means controlled by the moving of a bar into the slot 40 in the slotted member for releasing the coin controlled means for moving all of the locking means to unlocked position and allowing the locking 45 means for the delivery mechanisms to be moved to locked position.

50 2. In a vending machine having a plurality of compartments for holding articles of merchandise, each compartment being provided with a delivery mechanism for delivering one article at a time from a compartment, individual means for 55 operating each of the delivery mechanisms, means associated with each delivery mechanism and movable by gravity for normally locking the delivery mechanism against movement, a swingable bar movable by gravity to engage all of the said 60 locking means, and holding the same in unlocked position, coin controlled means for allowing the swingable bar to move downwardly and engage all of the means for locking the delivery mechanisms against movement and moving same to 65 unlocking position, a sliding bar associated with and connected to each delivery mechanism, and being movable by a delivery mechanism when a delivery mechanism is operated, means inhibiting extreme displacement of more than one bar at 70 a time as a result of dropping a coin into the apparatus, and means operable by the sliding of a bar associated with a delivery mechanism for releasing the coin controlled means and raising the swingable bar to allow all of the locking

means to engage and lock all of the delivery mechanisms against movement.

3. In a vending machine having a plurality of vertically disposed compartments disposed side by side and adapted to hold a column of articles of merchandise, an oscillatable delivery mechanism disposed at the lower end of each column, tension means normally holding each delivery mechanism in a position to support a column of merchandise, individual manually operable means associated with each delivery mechanism for rotating the delivery mechanism to deliver one article of merchandise at a time from a compartment, a pivoted dog associated with each delivery mechanism, and adapted to engage same normally to prevent rotation thereof, each dog having a laterally projecting tail, a pivoted wire or bail extending above each of said tails and adapted to fall by gravity onto the tails to release the dogs from contact with the delivery mechanisms, coin controlled means for allowing the bail to fall to release all of the delivery mechanisms for operation, a bar associated with and movable by each delivery mechanism upon actuation of a delivery mechanism to raise said bail and to allow the pivoted dogs to fall to locking position, a pivoted member having a slot therein adapted to be penetrated by one of said bars, and being of sufficient width to allow passage of only one bar

at a time to thereby prevent actuation of more than one delivery mechanism upon the insertion of a coin.

4. In a vending machine having a plurality of compartments for supporting columns of merchandise, each compartment having a delivery mechanism for supporting a column of merchandise, and when moved being adapted to deliver the lowermost article from a column to the exterior of the machine, means normally holding each delivery mechanism in non-delivery position, means for moving a delivery mechanism to deliver the lowermost article supported thereby to the exterior of the machine, means for normally locking all of the mechanisms against operation, coin controlled means for simultaneously unlocking all of the delivery mechanisms, a movable bar associated with each delivery mechanism, a movable member having a slot through which only one slideable bar at a time may pass thus permitting actuation of only one delivery mechanism after the insertion of a coin, and means controlled by the slideable bars for again locking all of the delivery mechanisms when one of the delivery mechanisms has been operated to deliver an article of merchandise to the exterior of the machine.

WILLIAM D. YOUNG.
WILLIAM ANDREW HARRIS.
